UNITED STATES PATENT OFFICE

2,395,834

DRYING OVEN

William Bald, Lowell, Ind., assignor to American Can Company, New York, N. Y., a corporation of New Jersey

Application March 31, 1942, Serial No. 437,074

6 Claims. (Cl. 34—150)

The present invention relates to drying ovens and has particular reference to drying or baking lithographed or lacquered sheets of metal. This is an improvement over United States Patent 1,591,683, issued July 6, 1926, to C. G. Preis.

An object of the invention is the provision of a sheet metal drying oven wherein a uniform heat distribution with a uniform temperature is maintained throughout the entire length of the oven.

Another object is the provision of such an oven wherein its various component parts are arranged in a manner that permits of free expansion and contraction under high temperature operating conditions.

Numerous other objects and advantages of the invention will be apparent as it is better understood from the following description, which, taken in connection with the accompanying drawings, discloses a preferred embodiment thereof.

Referring to the drawings:

Figure 1 is a top plan view of the entrance end of an oven embodying the instant invention, with parts broken away;

Figure 2 is a side elevation of the portion of the apparatus shown in Fig. 1, with the parts broken away;

Fig. 3 is a top plan view of the discharge end of the oven shown in Fig. 1 and continuing from the left in that figure, Figs. 1 and 3 when joined showing the complete oven with parts broken away;

Fig. 4 is a side elevation of the portion of the oven shown in Fig. 3, with parts broken away, and showing sheets in place in the oven;

Fig. 5 is a top plan view of a sheet feeding mechanism constituting a part of the oven apparatus located at the entrance end of the apparatus at the right in Fig. 1, and also such devices at the discharge end of the oven as viewed on a smaller scale at the left in Fig. 3, with parts broken away;

Fig. 6 is a side elevation of the mechanism illustrated in Fig. 5, also with parts similarly broken away, and showing sheets in place in the mechanism;

Fig. 7 is an enlarged side elevation of the upper portion of the oven near its entrance end as viewed in Fig. 2, with parts broken away;

Fig. 8 is a top plan view of the portion of the apparatus shown in Fig. 7, with parts broken away;

Fig. 9 is a side elevation showing a continuation of the apparatus shown in Fig. 8, the parts being

located at the upper left in that figure, with parts broken away;

Fig. 10 is a transverse sectional view taken substantially along the line 10—10 in Fig. 9;

Fig. 11 is an enlarged side elevation of the entrance end of the machine, with parts broken away;

Fig. 12 is a fragmentary elevational view taken substantially along a plane indicated by the line 12—12 in Fig. 8, and showing an explosion door;

Fig. 13 is a sectional view taken substantially along the line 13—13 in Fig. 12;

Fig. 14 is an enlarged fragmentary sectional detail showing the hinge construction of the explosion door in Fig. 13;

Fig. 15 is an enlarged sectional view taken substantially along the line 15—15 in Fig. 2, and showing a sheet in place in the oven;

Fig. 16 is a sectional detail taken substantially along the line 16—16 in Fig. 15, with parts broken away;

Fig. 17 is an enlarged sectional view taken substantially along the line 17—17 in Fig. 16, with parts broken away;

Fig. 18 is an enlarged side elevation of a cooling section of the oven apparatus shown at the left in Fig. 4, with parts broken away;

Fig. 19 is a transverse section taken substantially along the line 19—19 in Fig. 18, with parts broken away;

Fig. 20 is an enlarged sectional view taken substantially along the line 20—20 in Fig. 2, and showing a sheet in place in the oven;

Fig. 21 is a sectional view taken substantially along the broken line 21—21 in Fig. 7, and showing a sheet in place in the oven;

Fig. 22 is an elevational detail as viewed along a plane indicated by the line 22—22 in Fig. 21;

Fig. 23 is an enlarged perspective view of the oven frame and shell construction, with parts broken away;

Fig. 24 is an enlarged elevational detail of parts located at the discharge end of the oven as viewed in Fig. 4, with parts broken away;

Fig. 25 is an enlarged fragmentary sectional detail taken transversely of the oven in the center and is a section similar to that shown in Fig. 17 and indicating certain oven connections with the machine frame;

Fig. 26 is an enlarged sectional detail showing the upper rail secured to the frame at the middle; and

Fig. 27 is an enlarged sectional detail showing the lower rail secured to the frame at the middle.

As a preferred embodiment of the instant in-

vention the drawings illustrate a drying oven of the character disclosed in the above mentioned Preis patent and one in which metallic lithographed sheets A standing on edge are moved slowly through a heated chamber B so that the lithographing on the sheets will become baked thereon. After this baking operation the sheets are cooled to permit handling for subsequent operations.

The heating chamber B is divided into two connecting compartments, a front compartment through which the sheets first pass and a rear compartment into which the sheets pass from the front compartment. These compartments are enclosed by an arch shaped chamber casing 31 (Figs. 1, 2, 3, 4 and 15) which in some installations may be approximately eighty five feet long and which is made from a plurality of sheet metal transverse sections 32 bolted together. Each section comprises a sheet metal wall 33 secured to a pair of end angle irons 34 and a pair of bottom channel irons 35. The end angle irons of adjacent oven sections abut as shown in Fig. 23 and are tied together by bolts 36. A gasket 37 interposed between the angle irons provides a leakproof joint.

The two outer oven sections 32 and the middle section are formed with transverse walls 38 each having a rectangular opening 39 therein just large enough to permit the passage of the sheets A therethrough. These walls on the end sections block off the ends of the oven, while the middle wall separates the front and rear compartments.

In such a long oven considerable elongation takes place due to expansion of the sections when the oven is operating under high temperature conditions. To compensate for this elongation the bottom channel iron 35 of each section 32 of the oven is formed with a depending shoe 41 (Fig. 23) which rests on an inverted channel rail 42 extending longitudinally of the oven for its entire length. The shoe of the middle section of the oven is bolted to the rail while the other shoes are free to slide on the rail. Thus the middle section remains stationary while the other oven sections are free to expand in opposite directions from the middle section and thus are prevented from buckling. The upright sides of the channel rails 42 keep the oven sections in line and prevent lateral displacement.

The channel rails 42 are bolted to longitudinal and horizontal angle iron supports 44. These supports are secured to transverse leg sections 45 that rest upon a suitable foundation 46. The supports and the leg sections constitute the main frame of the apparatus.

The exterior surface of the oven sections 32 are covered preferably with heat insulating material 51 and this is held in place by an outer sheet metal shell 52. The lower edges of the shell extend down adjacent the angle iron supports 44 and are bent under and upwardly around the lower edges of the angle irons to secure the shell in place.

The interior of the oven casing 31 is formed with heating channels or spaces 61, 62 (Fig. 15) for circulating a heating medium, such as heated air, through the oven chamber and adjacent the sheets A passing therethrough. These heating channels are disposed adjacent the inside surface of the oven casing and are set off by a sheet metal wall section or shell 63 located in spaced and parallel relation to the oven casing. This wall section or shell is secured in place by spacer

blocks 64 which are bolted to the wall section and to the oven casing.

Each oven section 32 is formed with one of these walls 63 so that the channels 61, 62 are continuous throughout the two heating compartments of the chamber. The end and middle walls 38 of the corresponding oven sections 32 block off the outer and inner ends of the channels so that each channel is confined to its corresponding compartment. A radial division plate 66 located near the arched top of the oven sections and interposed between the wall section 63 and the oven casing 31 separates the channels 61, 62.

Heated air introduced into the channel 61, in a manner to be hereinafter explained, passes down in the direction of the arrows and through the heating space toward the bottom of the oven, as viewed in Fig. 15. Adjacent the bottom of the oven a curved deflector 68 having a plurality of vertical transverse vanes 69 (Fig. 16) directs the air upwardly through an opening 70 (see also Fig. 17) which is restricted or controlled by a hinged damper 71. The deflected air passes into the chamber B and travels upwardly along the inner curved wall section or shell 63 and adjacent the sheets moving through the chamber.

As the hot air crosses the arched portion of the wall section and travels downwardly along the opposite side of the chamber it tends to spread out and come into direct contact with the sheets being dried. This is prevented during the first part of the drying operation in order to avoid burning of the still wet lithographing as by a longitudinal deflector plate 74 (Fig. 15) which extends along this side of the chamber for a distance of approximately two thirds of the length of the front heating compartment. The deflector plate is supported on brackets 75 which are secured to the inner surface of the wall section 63.

After leaving the deflector plate 74, the heated air passes downwardly and along the bottom of the chamber toward the curved deflector 68. The deflector is formed with a downwardly curved member 77 that directs the air through an opening 78 which is regulated by a slide damper 79 (Fig. 17) carried in suitable slideways formed in the bottom section of the wall or shell 63. Air entering this opening passes into the heating channel 62 through which it moves upwardly along the oven casing toward the channel dividing plate 66. At the dividing plate the air is exhausted, reheated and again circulated through the oven in a manner which will be hereinafter explained.

Regulation of the dampers 77, 79 disposed adjacent the curved deflectors 68, 77 is effected from outside the oven (see Fig. 17). For this purpose the hinged damper 71 is pivotally connected to the inner end of a horizontally disposed link 81. The link extends across the deflector 68 and terminates in an adjusting bracket 82 (see also Fig. 16) secured to the outer surface of the oven casing 31.

The terminal end of the link is formed preferably with a universal joint ball 83 which is retained in any suitable manner in a threaded adjusting nut 84. The nut is located in a threaded bore 85 formed in the bracket 82. Thus by rotating the nut with a suitable tool such as a wrench, the link 81 is moved horizontally and the hinged damper 71 is hinged into a desired position to regulate the size of the opening restricted there-

by. There is one of these damper regulating devices for each section 32 of the oven.

In a similar manner the sliding damper 79 is shifted into a desired position to regulate the opening 78. For this purpose the damper is pivotally connected to the inner end of a link 91 that extends adjacent to and parallel with the link 81. The outer end of the link 91 is formed with a universal joint ball 92 which is confined in an adjusting nut 93 threadedly disposed in a bore 94 in the bracket 82.

The heating medium for the oven chamber B is supplied by way of a sheet metal duct 101 (Figs. 1, 2, 3, 4 and 7) which is mounted on top of the chamber casing 31. There are two of these ducts, one located near each end of the casing for supplying each chamber compartment independently. One end of the duct is connected to a centrifugal fan blower 102. In order to prevent undue vibration of the oven, the blower is carried on a separate auxiliary frame 103 that straddles the oven. The fan is mounted on a shaft 105 which is journaled in bearings 106 formed in a bracket 107 bolted to the auxiliary frame. The inner bearing 106 which is located nearest the duct is cooled by water circulated through pipes 111 connecting with a supply tank 112 mounted on the auxiliary frame.

The fan of the blower 102 is rotated at high speed by way of a belt 114 that operates over a pulley 115 mounted on the fan shaft 105 and over a pulley 116 (Figs. 1 and 8) which is carried on a driving shaft of an electric motor 117. The motor is supported on the auxiliary frame 103 and is actuated from any suitable source of electric energy.

The blower 102 is connected to an intake hood 121 (Figs. 1, 3, 12, 13 and 21) which is mounted on the chamber casing 31 and which communicates with the exhaust heating passageway 62 of the heating chamber. It is by way of this connection that the heated air after circulating through the oven is drawn up by the blower 102 into the heating duct 101 for reheating and for re-circulation through the oven. Fresh air is drawn into the blower by way of a register 123 (see Fig. 22) which is provided in the side of the oven casing 31. This register includes a pair of register openings 124, the size of which may be regulated manually by a rotatable cover plate 125.

Air blown into the duct 101 is heated prior to being circulated through the oven, by a gas flame burner 131 (Figs. 7 and 8) which is located in one side of the duct. The burner is furnished with gas from a pipe line 132 which leads from a suitable supply of gas. The burner is ignited by means of a pilot light enclosed in the burner and this pilot is supplied with gas from a pipe line 133 which branches off from the main supply line. Air for gas combustion within the burner is supplied by a small blower 135 which connects with the burner and which is actuated by an electric motor 136. The blower and the motor are supported on a bracket 137 that extends out from the auxiliary frame 103.

The heated air passing through the duct 101 is directed into the oven chamber inlet channel 61 by way of an inlet hood 141 (see also Figs. 9 and 10). This inlet hood is secured to the tops of two of the oven sections 32, as shown in Figs. 2 and 4, and communicates with openings 142 (Fig. 20) therein that lead into the inlet channel 61. The bottom of this inlet hood is formed with an open grating 143 and with a plurality of

5 curved baffle plates 144 which extend down into the inlet channel and which deflect the heated air toward the inner end of the heating compartment which they serve. There is one of these inlet hoods for each heating compartment and they are of identical construction.

10 Between the burner 131 and the main blower 102 a vent stack 147 (Figs. 7 and 8) is provided in the duct 101 for venting the duct of unburned gas when the burner is first ignited. This vent stack is formed with a damper 148 which may be actuated as desired to provide the required venting action. Explosion doors 151, 152 (see also Figs. 12, 13 and 14) are also provided in the inlet hood 141 and in the intake hood 121 to prevent damage to the oven in case of an explosion of unburned gas which may collect in the duct 101. These doors fit tightly within openings formed in the hoods but are easily pushed out by an extra pressure created within the hoods. The door in the intake hood preferably is mounted on hinges so that it will swing open readily.

15 At the entrance end of the oven at the right in Figs. 1, 2 and 11) the chamber casing 31 is formed with a canopy 155 which curves downwardly over the freshly lithographed sheets A to be dried as they enter the heating chamber. This canopy section is bolted to the first oven section 32 and rests unattached on top of a pair of brackets 150. These project outwardly from a sub-frame 156 so that the canopy may slide on the brackets with the expansion and contraction of the oven sections. The sub-frame is mounted on a suitable foundation which may be the same foundation on which the main frame rests.

20 The canopy section 155 collects the fumes from the freshly coated sheets and these fumes are drawn off by an exhaust duct 157 which extends up from the top of the canopy. An exhaust fan 158 is located within the duct and is operated by an electric motor 159. The motor is disposed outside the duct on a bracket 160 of the auxiliary frame 103 and draws the fumes off to any suitable place of deposit.

25 The sheets to be dried are received from any suitable source of supply, such as a printing or coating machine and are conveyed through the oven on an endless chain conveyor 175 (Figs. 4, 5, 6 and 15). The conveyor includes a pair of spaced and parallel chains 176 having closely spaced wickets or flights 177 secured thereto and extending along its entire length. These chains operate over two pairs of driving sprockets 30 181, 182. One pair is located at each end of the oven. There are two pairs of idler sprockets 183, 184, one pair being disposed adjacent each pair of the driving sprockets.

35 The driving sprockets 181 are located at the feed-in or entrance end of the oven and are mounted on a driving shaft 186 journaled in bearings 187 formed in a movable bracket 188 secured by bolts 189 to the top of the sub-frames 156. The driving shaft is rotated by a driving sprocket 192 mounted on the shaft and connected by an endless chain 193 to a speed reduction unit 194. The reduction unit is operated by a chain 195 which is actuated preferably by a main electric motor (not shown). This motor 40 preferably is used to drive the coating or printing machine that applies the lithographing to the sheets A.

45 The idler sprockets 183 are located at the entrance end of the oven and are disposed between 40 the upper and lower runs of the conveyor chains

to maintain them in spaced relation. These idler sprockets are mounted on a cross-shaft 201 carried in bearings 202 formed in the movable bracket 188.

The driving sprockets 182 at the opposite or discharge end of the oven are mounted on an auxiliary driving shaft 205 journaled in bearings 206 formed in a sub-frame 207 which rests on the oven foundation. This auxiliary driving shaft is driven by a sprocket 208 which is mounted on one end of the shaft. The sprocket is rotated by an endless chain 211 that operates over a driving sprocket 212 mounted on the rotor shaft of a synchronous electric motor 213. Motor 213 is actuated in synchronism with the main motor hereinbefore mentioned.

The idler sprockets 184 are located at the discharge end of the oven and are mounted on a cross-shaft 215 carried in stationary brackets 216 secured to a pair of cross-rails 217 which constitute a part of the sub-frame 207. These idler sprockets 184 operate against the lower runs of the conveyor chains and maintain these runs in spaced relation to the upper runs at this end of the oven.

In such long chains considerable stretch often results and provision is made for taking up this stretch at both ends of the oven. Any permanent stretch is taken up at the entrance end of the oven by shifting the movable bracket 188. For this purpose the bolts 189 which hold the bracket extend through elongated slots 221 in the bracket.

The bracket 188 is shifted manually by turning a handle 222 which is secured to a cross-shaft 223 carried in bearings formed in a pair of housings 224 secured to the sub-frame 156. Within the housings the cross-shaft carries a pair of worms which mesh with worm-wheels carried on a pair of rotatable rams 225. The rams abut against the inner edge of the movable bracket 188 and when the bolts 189 are loosened and the handle 222 is rotated, the rams are rotated against the bracket and slide it along the top of the sub-frame. This movement of the bracket carries driving sprockets 181 and idler sprockets 183 along with it and thus draws the conveyor chains taut.

At the discharge end of the oven, the conveyor chains are maintained in a taut condition by a pair of weight arms 231 (Figs. 5 and 6) secured to the outer ends of a cross-shaft 232. The cross-shaft carries a pair of tightener sprockets 234 that rotate against the lower run of the conveyor chains. The cross-shaft is carried in a pair of swing arms 235 loosely mounted on the auxiliary drive shaft 205. Weights 236 secured to the weight arms press the tightener sprockets against the conveyor chains and thus maintain them in a taut condition.

Between the driving sprockets 181, 182, the upper and lower runs of the conveyor chains are supported and are maintained in a horizontal spaced relation by longitudinal conveyor rails 241. At spaced intervals, the chains carry outwardly projecting rollers 242 that ride on these conveyor rails (see also Fig. 15). The rails extend the full length of the conveyor and are carried loosely in grooved or slotted brackets 243 bolted to the cross-rails of the frame and to the sub-frames of the oven and also on the bottom section of the channel wall 63 which constitutes the bottom of the oven chamber

(Fig. 15). The rails at their intermediate portions are bolted to the slotted brackets.

Hence the rails 241 are free to expand in opposite directions and thereby buckling of the rails or creeping in the direction of travel of the conveyor is prevented. The loose connection between the brackets and the rails permits of this expansion while maintaining the rails in place against lateral displacement.

The conveyor travels through the oven very slowly and carries the sheets in an upright position or on edge as shown in Fig. 6. Upon completing this travel through the oven, the conveyor continues on through a cooling unit 250 (Figs. 3 and 4) in which the high temperature of the baked sheets is reduced sufficiently to permit handling.

The cooling unit 250 includes a rectangular sheet metal housing 251 (Figs. 18 and 19) having an opening 252 in each end large enough to permit the passage of a sheet A therethrough. The housing extends below the upper run of the conveyor 175 and is supported on an auxiliary frame 253 which is a continuation of the main frame 45. The housing located below the upper run of the conveyor, carries three cooling fans 255 that are mounted on the rotor shafts of three separate electric motors 256 located directly below the conveyor. These motors are actuated from any suitable source of electric energy. Adjacent the motors the housing is connected to a fresh air inlet duct 257 that extends upwardly alongside the housing.

Hence when the motors 256 are in operation, the fans 255 draw in fresh air from the duct 257 and blow it upwardly between the sheets A passing through the housing. It is this air that cools the sheets. Air circulated between the sheets is caught by a plurality of exhaust fans 261 located directly above the path of travel of the sheets. There are three of these fans and they are rotated by three separate electric motors 262 that are actuated from any suitable source of electric energy. These fans draw the air up between the sheets and blow it out through an exhaust stack 263 formed on top of the housing 251.

In order to prevent undue chilling of the sheets A as they pass through the cooling section, provision is made to recirculate a part of the air that is forced up between the hot sheets. For this purpose there is a by-pass connection 265 between the air inlet duct 257 and the cooling housing 251. The opening in this by-pass connection is regulated by a damper 266 which may be actuated manually or otherwise. Under cold weather conditions when the fresh air entering the duct 257 may be too cold, it may be modulated or tempered by adjustment of the damper so that a portion of the air blown on the sheets and partially heated thereby may be directed through the by-pass and thus mix with the fresh air to reduce its temperature to within desired limits.

After leaving the cooling section 251 the cooled sheets A are ready for discharge from the conveyor. This may be performed manually or automatically as desired. Usually the sheets are removed manually and are arranged in stacks on hand trucks for subsequent operations. This removal of the sheets is facilitated by a pair of inclined, stationary lifter rails 271 (Figs. 5, 6 and 24) which raise the sheets as they are advanced adjacent the discharge end

of the conveyor so that they may be readily grasped by the operator.

The lifter rails 271 preferably are straight for their major extent and are formed with a curved discharge end 272. There are two of these lifter rails located one on each side of the conveyor 175. The straight portion of the rails are formed with depending lugs 273 having elongated slots 274 through which clamping bolts 275 extend into stationary brackets 276 mounted on the cross rails 217 of the auxiliary sub-frame 207. The curved ends of the lifter rails are formed with lugs 277 which are pivotally connected to slotted links 278 bolted to brackets 279. Brackets 279 are secured to the driving shaft bearings 206 of the auxiliary sub-frame. With this construction of support members for the lifter rail adjustment may be made to any desired inclination and height to facilitate removal of the sheets.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A drying oven for lithographed metal sheets comprising in combination, a frame, an elongated casing enclosing a drying chamber mounted on said frame, a conveyor operating through said chamber for carrying lithographed metal sheets to be dried, longitudinally disposed spaced rails for supporting said conveyor, a transverse wall within said casing and dividing said chamber into separate compartments, said wall having an opening therein for the passage of the conveyor and the sheets therethrough, a plurality of heating devices for individually heating the chamber compartments to maintain predetermined temperatures therein, and means for securing said rails at their intermediate portions to said frame to permit longitudinal expansion of the rails in opposite directions from their secured intermediate portions under varying temperature conditions.

2. A drying oven for lithographed metal sheets, comprising in combination, a casing enclosing a drying chamber and having a supporting frame, means for heating said chamber, a conveyor operating through said chamber for carrying lithographed metal sheets to be dried, and continuous rails extending through said chamber for guiding the conveyor, each rail being secured at its intermediate portion to said frame and being free throughout the remainder of its length, to allow unrestricted longitudinal expansion under high temperatures thereby preventing creeping of the rails in the direction of travel of the conveyor.

3. A drying oven for lithographed metal sheets comprising in combination: a frame, a plurality of oven sections secured together to provide a casing enclosing an elongated drying chamber mounted on said frame, means for heating said chamber, an endless conveyor operating through said chamber for carrying lithographed metal sheets to be dried, longitudinally disposed spaced rails mounted on said frame for supporting said

conveyor, a runway on said frame for loosely supporting said casing sections so that the same are free to expand under high temperatures in the chamber, and means for securing said rails at their intermediate portions to said frame to permit longitudinal expansion of the rails in opposite directions from their secured portions under varying temperature conditions.

4. A drying oven for lithographed metal sheets comprising in combination, a frame, an outer casing enclosing a drying chamber mounted on said frame, a conveyor operating through said chamber for carrying lithographed sheets to be dried, longitudinally spaced rails in said chamber for supporting said conveyor, means for circulating heated air through the chamber for drying the sheets moving therethrough, means disposed adjacent the discharge end of said conveyor for elevating the sheets to a desired position in readiness for discharge from the conveyor, and means for securing the intermediate portions of said rails to said frame to permit longitudinal expansion of the rails in opposite directions from their secured portions under varying temperature conditions.

5. A drying oven for lithographed metal sheets comprising in combination, a frame, an outer casing enclosing a drying chamber supported by said frame, an endless conveyor operating through said chamber and including spaced wickets for carrying lithographed sheets on edge to be dried in said chamber, longitudinally disposed spaced rails in said chamber for supporting said conveyor, means for circulating heated air through said chamber for drying the sheets moving therethrough, a pair of adjustable inclined rails disposed adjacent said conveyor at its discharge end for raising the sheets above said wickets as they ride up on said rails so that the sheets may be readily grasped for removal from the conveyor, and means for securing said longitudinally spaced rails at intermediate portions thereof to said frame to permit longitudinal expansion of the rails in opposite directions from their said secured portions to compensate for varying temperature conditions.

6. A drying oven for lithographing metal sheets, comprising a sectional casing enclosing a drying chamber, a conveyor for carrying the sheets in an upright position through said chamber, a heating wall in each of the sections of said casing and spaced from the casing to constitute therewith an air passage extending substantially around the outer part of said chamber, independent means at opposite ends of said chamber for directing heated air inwardly through said passage, means for circulating said heated air transversely to the path of travel of said sheets through said chamber and immediately around the moving sheets on said conveyor, a pair of separate spaced movable dampers disposed in one of said casing sections respectively at opposite ends of the transverse path of travel of the heated air within the chamber for controlling the flow of heated air through said passage, and means disposed in said casing and operable from exterior thereof for independently and selectively shifting said dampers to a desired position, whereby to vary the volume of the heated air admitted to said chamber.
